UNITED STATES PATENT OFFICE.

INEVA TAGLLONIA REILLY, OF INDIANAPOLIS, INDIANA.

TOMBSTONE.

Application filed October 23, 1922, Serial No. 596,341. Renewed November 1, 1923.

To all whom it may concern:

Be it known that I, INEVA T. REILLY, a citizen of the United States, residing at Indianapolis, in the county of Marion and State of Indiana, have invented certain new and useful Improvements in Tombstones; and I do declare the following to be a full, clear, and exact description of the invention, such as will enable others skilled in the art 10 to which it appertains to make and use the same.

My invention relates to improvements in tombstones and more particularly to head stones, the object being to provide a stone 15 having a novel form of base which assists in anchoring the stone and also serves to contain growing plants or cut flowers, as occasion may require, a suitable container 20 being preferably provided for the cut flowers.

With the foregoing in view, the invention resides in the novel subject matter herein-after described and claimed, the description being supplemented by the accompanying 25 drawing.

Figure 1 is a front elevation.

Figure 2 is a side elevation.

Figure 3 is a vertical sectional view as indicated by line 3—3 of Fig. 1, showing 30 a container within the base for cut flowers.

Figure 4 is a view similar to Fig. 3 but illustrating the manner in which the base is used to contain growing plants.

In the drawing above briefly described, the 35 numeral 1 designates a head stone of any desired shape, the lower end 2 of said head stone being reduced and having a flat front side 3 with a shoulder 4 facing downwardly and disposed at the juncture of the side 3 with the remaining front side portion of 40 the stone. At the front of the stone 1, I provide a horizontally elongated base block 5 having a flat rear side which fits against and is cemented to the side 3 of the reduced stone 45 end 2, the shoulder 4 then resting upon the block 5 as shown. The block 5 is elongated in a direction parallel with the front side of the stone 1 and is of a length greater than the width of said stone as shown in Fig. 1, 50 whereby it serves to effectively anchor the stone when inset in the earth.

The block 5 is provided with an opening 6 extending substantially throughout its length and width and passing from its top through its bottom, the wall of this opening being preferably provided with an upwardly facing shoulder 7 upon which a sheet metal container 8 may rest when positioned in the upper portion of the opening 6, for the purpose of containing cut flowers, as 60 shown in Figs. 1, 2 and 3. The several sides of the container 8 are preferably tapered downwardly to some extent so as to facilitate insertion and removal and to also permit a number of the containers to be readily nested 65 while shipping or storing, before they are sold to the user.

If desired, the container 8 may be removed and growing plants may be planted within the opening 6, as disclosed in Fig. 4. 70

The invention may be embodied in a number of different sizes and proportions and obviously any desired materials may be employed.

I claim:

1. A head stone having a base adapted to be inset in the earth to assist in anchoring the stone, said base extending forwardly from the head stone and being elongated in a direction parallel to the front side of the 80 stone with its end portion extending beyond the head stone and the base having an opening entirely from its top to its bottom to receive either growing flowers or a container of cut flowers. 85

2. A head stone having a reduced lower end and a downwardly facing shoulder across its front side at the juncture of said reduced end with the remainder of the stone, a horizontally elongated base 90 block of greater length than the width of said stone having its rear side fitting against the front side of said reduced stone end, said block being in contact with said shoulder of the stone and having an opening to receive flowers or plants. 95

In testimony whereof I have hereunto affixed my signature.

INEVA TAGLLONIA REILLY.
